His Attorney
The C. & S. Company

United States Patent Office.

CLAUD H. D'ARCUS, OF DETROIT, MICHIGAN.

Letters Patent No. 98,851, dated January 18, 1870.

IMPROVED ADJUSTABLE RECLINING-CHAIR.

The Schedule referred to in these Letters Patent and making part of the same.

To whom it may concern:

Be it known that I, CLAUD H. D'ARCUS, of Detroit, in the county of Wayne, and State of Michigan, have invented a new and useful Improvement in Adjustable Reclining-Chairs; and I do declare that the following is a true and accurate description thereof, reference being had to the accompanying drawings, and to the letters of reference marked thereon, and being a part of this specification.

Figure 1 is a perspective, and

Figure 2, a rear elevation of my invention.

Like figures indicate like parts in each figure.

The nature of my invention relates to an improved and simplified construction of that class of chairs known as invalid or reclining-chairs; and

It consists in so arranging the various parts of the chair that the occupant can, at will, compel the chair to assume any desired reclining position, and secure it in such position by means of self-acting ratchets.

It further consists in a self-adjusting arm, which operates in unison with the various positions of the chair.

In the drawings—

A represents the posts of the frame, which form the front legs of the chair and the support of the back, and, in chairs for the use of adults, should be about four feet long.

A cross-bar, *a*, of any desired length, connects these posts together at the bottom, and a similar cross-bar, not shown in the drawings, connects the top of the posts *A*.

Two other posts, *B*, similarly connected by cross-bars, at each end, and curved in the form shown in the drawings, in such a manner that they form the seat-frame and rear legs of the chair, are pivoted between the posts *A*, at *b*. In chairs for the use of adults, these posts *B* should be about twenty-six inches long, and pivoted to the posts *A*, about fifteen inches from the lower ends of said latter-named posts.

A strip of carpeting or other suitable material, about four feet long, is secured to the front cross-bar, between the posts *B*, and to the top cross-bar between the posts *A*, at each end of said strip, and forms the seat and back of the chair.

The arms *C* are formed of strips of webbing, leather, or other suitable material, one end of which should be secured to the front of the posts *A*, about ten inches above the axis of the seat. Thence they are led forward to and over the rounded or curved front of the arms *D*, which are secured to the forward ends of the

posts *B*; and thence backward, and their opposite ends secured to the front of the posts *A*, about ten inches below the axis of the seat.

These arms are secured in their position over the arms *D* by means of loops *c* or any other convenient device, which will allow the strips which form the arms to be drawn through said loops.

About ten inches above the lower ends of the posts *B*, there extends, between said posts, and secured thereto, an iron rod, *d*.

Pendent from the seat-frame, are the racks or ratchet-bars *E*, whose lower ends are connected by a bar, *e*, in such a manner as to make the movement of said rack-bars simultaneous.

A cord, *f*, attached to the lower ends of said rack-bars, leading upward, passes through a ring or other suitable device, secured to the cross-bar, which connects the tops of the posts *A*, and is intended to enable the operator to disengage the teeth of the rack-bars from the iron rod *d*, as more fully hereinafter described.

The rack-bars should be so hung, that they will at all times engage with said rod, except when disengaged by the occupant of the chair.

The chair being in an upright position, as shown in the drawings, the occupant, by pulling upward on the cord, releases the rack-bars from the rod, and, leaning back in the chair, assumes such position as he desires; when, releasing the cord, the rack-bars engage with the rod, and secure the chair in the required position. At the same time, the arm-straps, sliding through the loops, are kept "taut," and form convenient rests for the arms of the occupant.

The proportions of this chair may be varied to suit circumstances, for adults or children, as may be desired.

What I claim as my invention, and desire to secure by Letters Patent, is—

1. In reclining-chairs, the arm *C*, in connection with the posts *A* and arms *D*, when arranged and operating as specified.

2. The arrangement of the posts *A* *B*, cross-bars *a*, arms *C* *D*, loops *c*, iron rod *d*, ratchet-bars *E*, and cord *f*, with any suitable material, to form the seat and back of a chair, when constructed and operating as herein described.

C. H. D'ARCUS.
